US00D924847S

(12) **United States Design Patent** (10) **Patent No.:** **US D924,847 S**
(45) **Date of Patent:** **** Jul. 13, 2021**

(54) **BLUETOOTH HEADSET**

(71) Applicant: **Xiaoqian Xie**, Zhuzhou (CN)

(72) Inventor: **Xiaoqian Xie**, Zhuzhou (CN)

(**) Term: **15 Years**

(21) Appl. No.: **29/719,946**

(22) Filed: **Jan. 8, 2020**

(51) LOC (13) Cl. **14-01**

(52) U.S. Cl.

USPC **D14/223**

(58) **Field of Classification Search**

(57) **CLAIM**

The ornamental design for a Bluetooth headset, as shown and described.

DESCRIPTION

FIG. 1 is a front perspective view of a Bluetooth headset showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective thereof, shown being received inside a box.

The broken line showing of the box in FIG. 9 depicts environment and forms no part of the claimed design. All other broken lines depict portions of the Bluetooth headset that form no part of the claimed design.

1 Claim, 9 Drawing Sheets
